(57) **CLAIM**

The ornamental design for a wheel, as shown and described.

DESCRIPTION

FIG. 1 is a top, front, right-side perspective view of a wheel design,

FIG. 2 is a front elevation view of the wheel design,

FIG. 3 is a top plan view of the wheel design being

rotationally symmetric,

FIG. 4 is a full cross-section view of the wheel design taken

along line 4-4 of FIG. 2; and,

FIG. 5 is a partial cross-section view of the wheel design,

shown at an enlarged scale, taken along line 5-5 of FIG. 2.

The broken lines shown are included for the purpose of

illustrating the unclaimed portions of the wheel design and

form no part of the claim.
